LOCK

Olin Polson, Chicago, Ill.

Application August 11, 1941, Serial No. 406,269

8 Claims. (Cl. 292—195)

The invention relates generally to locks and more particularly to a lock for hinged members such as doors or casement windows.

The general object of the invention is to provide a combined lock and seal for a hinged member such as a door, window or the like.

More specifically, it is an object to provide a locking device for a hinged member adapted to be mounted in the free or opening edge of the member and coextensive with said edge so that the hinged member is locked along its entire opening edge, the device also serving as a seal or weather strip for said edge when moved to its locking position.

A further object is to provide a novel lock which not only serves as a seal along the locked edge of the hinged member, but also causes the window to firmly bear against the stop extending along said edge so that, in addition to being locked, the hinged member is doubly sealed along said edge.

Another object is to provide a novel lock for a hinged member such as a door or casement window, which cannot be forced open, which is easy to operate, and which is low in cost.

Still another object is to provide a novel sealing construction for both the hinged edge and the opening edge of a casement window or the like.

A still further object is to provide a novel window construction having a metal frame member adapted for use between two adjoining casement windows, the frame member cooperating with a lock on the opening edge of the sash of one window for locking and sealing that sash and cooperating with the hinged edge of the other sash for effecting a seal along said edge.

Other objects and advantages will become apparent from the following description, taken in connection with the accompanying drawings, in which:

Figure 1 is a horizontal sectional view of a casement window embodying the features of the invention.

Fig. 2 is a vertical sectional view thereof taken on the line 2—2 of Fig. 1.

Fig. 3 is a fragmentary sectional view taken on the line 3—3 of Fig. 1.

Fig. 4 is a fragmentary edge view of the sash of the window shown in Fig. 1.

Fig. 5 is a perspective view of the actuator utilized in the window shown in Fig. 1.

Fig. 6 is a horizontal sectional view of a modified form of window.

Fig. 7 is a horizontal sectional view of another modified form of window.

Fig. 8 is a horizontal section on a reduced scale of another modified form of window.

5 While the invention is adapted for any hinged element mounted within a surrounding frame element such as a door or the like, it is particularly adapted for use with a casement window. Generally, a device embodying the features of the invention is adapted to be mounted at the opening edge of the hinged element for the purpose of locking said element to the frame element and simultaneously providing a weather-tight seal. It is also of such construction that it may be mounted either in the edge of the hinged element to cooperate with the adjoining portion of the frame, or may be mounted in the frame to cooperate with the adjoining edge of the hinged element.

10 15 20 25 30 35 40 45 50 55 The preferred embodiment of the invention, when used in a casement window, comprises generally a member rotatably mounted in the opening edge of the sash and swingable from a position where it lies wholly within the perimeter of the sash, to a projecting position entering into a groove provided in the frame. The member thus locks the sash to the frame and also, because it is coextensive with the length of the sash, provides a weather-tight seal between the sash and frame along the entire length of said edge. Moreover, when the rotatable member swings into the groove in the frame into abutment with one side of the groove, it forces the sash against the stop ordinarily provided in such window constructions. The sash is thus doubly sealed. To rotate the member, a simple form of actuator is provided which has a manually operable handle extending to the inside of the sash. This form of lock is preferably utilized with a sash which also has sealing means provided around the other three sides thereof so that the sash is sealed on its entire perimeter.

In Fig. 1 I have shown a casement window construction comprising vertical frame members 10 and stops 11 on the inner side thereof against which a casement sash, indicated at 12, is adapted to abut when closed. The casement sash 12 includes a pair of side stiles 13, one of which (the left-hand stile in the present instance) is secured to the adjacent frame member 10 by hinges 14. The sash is thus adapted to swing outwardly. The stiles 13 and the top and bottom rails of the sash support the usual pane of glass 15 secured therein in the usual manner. As heretofore mentioned, the preferred em-

bodiment of the invention includes a member rotatably mounted in the opening edge of the sash to engage the adjacent frame member 10. While the rotatable member may have other forms than herein shown, in the preferred form such member comprises a generally cylindrical bar 20 extending the full height of the sash and rotatably supported therein by being mounted in a generally cylindrical recess 21 cut in the edge of the side stile 13. The recess 21 is of such size at its opening edge that the bar may be inserted therein from the edge of the sash. To retain the bar in place, a face plate 22 is secured as by screws 23 to the edge of the stile 13 and extends part way over the recess 21, leaving a gap opening into the recess. The bar 20, while of generally cylindrical form, is cut away at one side thereof to provide a lip portion 24 adapted to extend through the gap provided by the plate 22. When the bar 20 is rotated, it is adapted to swing from a position where the lip 24 lies within the perimeter of the sash to a position where the lip extends therebeyond and into a groove 25 cut in the frame member 10. The bar when it is thus rotated into the groove securely locks the sash to the frame.

Preferably the groove 25 is generally triangular in shape so that the lip portion 24 of the bar may abut against one side of the groove to form a seal, thereby effecting a weather-tight relationship between the sash and the frame for the entire length of that edge of the sash. Not only is the weather-tight relationship established along the entire edge, but also the locking relation is established along the entire edge so that the lock cannot be forced open.

This lock has a further advantage in that it forces the sash into tight abutment with the stop 11 of the frame. To this end, the protruding lip 24 and the notch 25 are so shaped that, as the bar 20 is rotated into locking position, it provides a camming action, forcing the sash firmly against the stop 11. Thus the sash is doubly sealed along the locked edge.

Means of simple construction are provided for readily rotating the bar 20 from its locked to its unlocked position. Said means comprises in its preferred form a member 30 of arcuate form and embracing a portion of the bar 20. Said member 30 is mounted for sliding movement along the bar in an inner recess 31 cut in the side stile 13 of the sash. To cause rotation of the bar 20 the member 30 is provided with a cam slot 32 into which extends a pin 33 mounted radially in the bar 20. Thus as the member 30 is moved along the bar 20, the cam slot 32 in cooperation with the pin 33 causes the bar 20 to rotate.

To slide the member 30 along the bar a hand lever 36 is provided which is pivotally connected as at 34 between a pair of lugs 35 extending from the rear face of the member 30. The hand lever 36 extends through a slot 37 cut in the side stile 13, and is pivotally supported by a pin 40. In order to compensate for the arcuate movement of the hand lever 36, the latter is loosely mounted on the pin 40 so that the member 30 may have a rectilinear movement. The outer end of the hand lever 36 is provided with a handle 41 which is thus movable in the plane of the sash to actuate the lock.

A seal is also provided at the hinged edge of the sash. Such seal preferably comprises a strip 42 (see Fig. 1) set into a groove in the frame member 10 at the hinged edge of the sash. The strip 42 extends beyond the frame member 10

and is adapted to seat itself in a groove 43 cut in the hinged edge of the sash. The strip 42 is adapted to abut against one face of the groove 43, when the window is closed, to provide the seal, but in order to facilitate entrance of the strip into the groove one side of the latter is cut away on a slant as at 44.

The top and bottom edges of the sash are likewise sealed. For this purpose I provide a strip of metal 45 (see Fig. 2), which extends parallel to but in slightly spaced relation to the edge of the sash. To hold the strip 45 in such position it is provided with an angularly bent portion 46 forced into a groove in the edge of the sash. The strip 45 is adapted to interleaf with two spaced strips 47 secured to the frame. Such strips 47 are preferably held in place by angularly bent portions 48 forced into grooves in the frame. Thus the sash is sealed around its entire perimeter.

In the modified form of construction shown in Fig. 6, I have shown a casement window adapted to swing inwardly. To this end the window comprises a pair of frame members 50 having stops 51 on the outer face thereof. The sash, indicated at 52, is hinged as at 53 to one of the frame members 50. The locking bar, indicated at 54, is of the same general form and is provided with a protruding lip 55 similar to the lip 24. However, the lip is on the opposite side of the bar and abuts against one side of its cooperating groove in the frame member 50 in such a manner as to cause the sash to be forced outwardly against the stop 51.

To rotate the bar 54 a lug 56 is formed thereon to extend into a recess 57 in the sash. The lug 56 is provided with a slot 60 cooperating with a pin 61 to form a lost-motion connection with a nut 62. The nut 62 is mounted on a screw 63 rotatably supported in a face plate 64 mounted on the inner face of the sash. To rotate the screw a handle 65 is provided on the inner side of the sash. By this construction, rotation of the handle 65 causes the nut 62 to be moved back and forth along the screw 63, thereby causing rotation of the locking bar 54. Such construction not only locks the sash to the frame throughout the entire height thereof, but also effects a tight seal between the protruding lip 55 and the groove in the frame member, as well as a seal between the sash and the stop 51. This sash may also be provided with sealing means at its other three edges similar to the means heretofore described.

In Fig. 7 I have shown another modified form of window construction in which there are two sashes, indicated at 70 and 71, in edge-to-edge relation and both hinged at their outer edges to the window frame. The sash 71 may be provided with the usual sliding bolts 72 mounted at its upper and lower edges for engagement with the upper and lower portions of the frame. The sash 71 is also provided with a molding 73 on its outer face protruding beyond the edge thereof and overlying the adjacent sash 70. In the sash 70 I provide a combined lock and seal similar to that shown in Figs. 1 to 5, inclusive, but arranged for an inwardly swinging sash. With such a combined lock and seal, the protruding lip 24 of the locking bar is adapted to extend into a groove 74 formed in the edge of the sash 71. Also the cam action of the protruding lip 24 against the side of the groove 74 causes the sash 70 to be cammed into sealing relation with the molding 73.

In the modified form of Fig. 8 I have illustrated a window comprising a plurality of sashes, three in the present instance, indicated at 80, 81 and 82. The window construction herein shown includes metallic frame members, indicated generally at 83, extending between adjoining sashes and also at the outer edges of the sashes 80 and 82. The frame members comprise strips provided at their outer edge with rounded molding portions 84 serving as stops for the sashes. Each strip is bent along a longitudinal line to provide a groove 85 to receive the locking bar, which preferably is of the form shown in Figs. 1 to 5, inclusive, and is mounted in the opening edge of the sash. The same bend in the strip also provides a protruding lip 86 adapted to interfit with a groove 87 cut in the hinged edge of the adjoining sash. Thus the frame member 83 is in sealing and locking relation on one side with the sash carrying the locking member and on the other side is in sealing relation with the hinged sash.

In the operation of the window shown in Figs. 1 to 5, inclusive, the window is swung inwardly to its closed position. The handle 41 is then depressed causing the member 30 to be raised. Such movement by the member 30, by virtue of its pin and cam slot connection with the bar 20, causes the latter to rotate and its protruding lip 24 to enter the groove 25 in the frame member 10. Locking is thereby effected. When the protruding lip 24 abuts against the edge of the groove 25, a seal is thus provided. Also, the cam action thereof forces the sash into tight abutting relation with the stop 11 so that the window is doubly sealed along that edge. Closing of the window also causes the strip 42 to enter the groove 44 in the hinged edge of the sash and to effect a sealing relation along that edge. To release the sash, the handle 41 is raised, causing the member 30 to move downwardly, thereby rotating the bar 20 so that the lip 24 of the bar lies within the perimeter of the sash. The sash is thus free to swing outwardly.

The forms of construction shown in Figs. 7 and 8 operate similarly. In the form shown in Fig. 7, the locking bar effects a lock between the two sashes 70 and 71, and also causes the sash 70 to abut firmly against the molding 73 on the sash 71. In the form shown in Fig. 8, the metallic frame members 83 by their bent formation provide both the groove for the locking member and also the sealing strip entering into the hinged edge of the adjoining sash. Furthermore, the frame members 83 are provided with a molding portion acting as a stop for the sashes.

The means for actuating the locking bar shown in Fig. 6 provides a simple rotatable handle 65 which, by a small amount of turning, causes the locking bar 54 to swing in and out of locking relation in the groove in the frame member.

From the foregoing, it will be apparent that I have provided a combined lock and seal for a hinged member such as a door, window or the like. The locking device is adapted to be mounted in the free and opening edge of the hinged member and is coextensive with said edge so that locking is effected along the entire hinge. The sash is doubly sealed along the edge by virtue of the fact that the lock itself forms a seal with the groove in the frame member and the locking bar by its camming action forces the sash into tight sealing relation with the stop on the frame.

I claim as my invention:

1. A lock for a casement window or the like 75

having a frame provided with a groove, said lock comprising, in combination, a bar rotatably mounted in the opening edge of the sash for movement into said groove in the frame, and means for rotating said bar comprising a member movable longitudinally of said bar and provided with a cam slot, a pin extending from said bar into said slot, and a hand lever for shifting said member longitudinally of the bar.

10 2. A lock for a casement window or the like having a frame provided with a groove, said lock comprising, in combination, a generally cylindrical bar rotatably mounted in the opening edge of the window sash and rotatable into locking engagement with said groove in the frame, and means for rotating said bar comprising a member embracing said bar and provided with a cam slot, a pin extending from said bar into said cam slot, and a hand lever for shifting said member longitudinally of the bar.

15 3. A lock for a casement window or the like having a frame provided with a groove, said lock comprising, in combination, a bar rotatably mounted in the opening edge of the window sash and rotatable into said groove in the frame, a member mounted in said sash and movable longitudinally of said bar, said member and said bar having cooperative cam means whereby upon movement of the member the bar will be rotated, and a hand lever for shifting said member, said hand lever being pivotally connected to said member and having a loose pivotal connection with said sash.

20 4. A lock for a casement window or the like having a frame provided with a groove, said lock comprising, in combination, a bar rotatably mounted in the edge of the sash for movement into and out of said groove in the frame, means for rotating said bar comprising a member mounted within the sash for movement longitudinally of said bar and having a cam connection therewith, and a lever for actuating said member and extending through the side stile of the sash for movement in the plane of the sash.

25 5. A lock for a casement window or the like having a frame provided with a groove, said lock comprising, in combination, a bar rotatably mounted in the opening edge of the sash for movement into the groove of the frame, and means for operating said bar comprising a manually operable rotatable screw member extending perpendicularly into the sash adjacent said bar, a nut on said screw, and a lug extending from said bar and having a lost motion connection with said nut whereby movement of the nut along the screw member will rotate said bar.

30 6. A lock for a casement window having a pair of sashes in edge to edge relation when closed with one of said sashes provided with a groove in its abutting edge and a molding on its outer face overlying the other sash, said lock comprising, in combination, a bar rotatably mounted in the abutting edge of said other sash and rotatable into said groove, said bar being coextensive with the length of said sashes, means for rotating said bar to force the bar against one side of the groove to form a primary seal between the two sashes and to force said other sash into sealing relation with said molding to form a secondary seal.

35 7. In a window construction for casement windows comprising a plurality of sashes and a metallic frame member extending between adjacent sashes at the opening edge of one and the hinged edge of the adjacent sash, said frame member comprising a strip having a bend providing both

a groove facing said one sash and a lip extending toward the adjacent sash, the combination with said frame member of locking means for said one sash comprising a bar rotatably mounted therein and coextensive with the length thereof, said bar having a lip swingable into locking and sealing relation with said groove, and manually operable means for rotating said bar, the adjacent sash being provided with a groove to receive said frame member lip in sealing relation therewith when the sash is closed.

8. A lock for a casement window or the like comprising a sash hinged within a frame and having a semi-cylindrical groove in its opening edge, said lock comprising, in combination, a bar rotatably mounted in said groove and coextensive with the length of said edge, said bar being seg-

mentally shaped in cross section and slightly greater than a semi-circle to provide a longitudinally extending lip, and said bar being rotatable within said groove from a position where the lip lies wholly within the groove to a position where said lip enters a groove in the frame in locking and sealing relation therewith, a strip mounted on said opening edge of the sash and extending across a portion of the groove in said edge leaving an opening for said groove through which the lip may be projected on rotation of said bar, and manually operable means mounted in said sash for rotating said bar, said strip serving to retain the bar within the groove in the sash.

OLIN POLSON.
